UNITED STATES PATENT OFFICE.

FRANK GLASGOW, OF OSCEOLA MILLS, PENNSYLVANIA.

ELECTRIC ALARM FOR TIME-PIECES.

SPECIFICATION forming part of Letters Patent No. 352,407, dated November 9, 1886.

Application filed May 1, 1886. Serial No. 200,827. (No model.)

To all whom it may concern:

Be it known that I, FRANK GLASGOW, of Osceola Mills, in the county of Clearfield and State of Pennsylvania, have invented a new 5 and useful Improvement in Electric Alarms for Time-Pieces, of which the following is a specification, reference being had to the annexed drawings, forming a part thereof, in which—

10 Figure 1 is a perspective view of a time-piece to which my improved electric alarm has been applied. Fig. 2 is a vertical longitudinal section of the base of the time-piece. Fig. 3 is a vertical transverse section taken on 15 line xx in Fig. 2.

Similar letters of reference indicate corresponding parts in the different figures of the drawings.

The object of my invention is to provide an 20 electric-alarm attachment to alarm-clocks to be operated by the alarm mechanism of the clock, so as to complete an electric circuit and sound an alarm electrically.

My invention consists of a base, upon which 25 is mounted an ordinary alarm-clock carrying on the spring-arbor of its alarm mechanism a crank, and in the combination therewith of an electrical contact-lever resting in a notch in the base and held normally out of contact with 30 the circuit-wire extending through the base, and a releasing-lever pivoted to the base and extending into the path of the crank on the spring-arbor of the alarm mechanism and arranged to release the contact-lever from its 35 notch in the base.

An ordinary alarm-clock, A, is mounted on the hollow base B, and upon the spring-arbor C of the alarm mechanism of the clock is supported an arbor-extension, D, which is apertured transversely and provided with a binding-screw, a. In the aperture of the extension D is inserted an arm, E, having its free end apertured transversely to receive a pin, b, which is clamped in the aperture in the 40 arm by the set-screw c. As the alarm mechanism of the clock A is of the usual well-known kind no further description of it will be required.

In the back of the base B is formed a right- 45 angled slot, d, in which is received the free end of a contact-lever, e, the opposite end of

which is jointed to an eye, f, projecting inward from the front of the base B. The eye f is connected with the binding-post F at the end of the base, and to the binding-post G is 55 secured a wire, g, which is stretched lengthwise across the base B, under the contact-lever e. To the back of the base B, above or near the right-angled slot d, and upon the screw h, is pivoted the lever i, which is held 60 with sufficient friction against the back of the base to prevent it from accidentally turning. The lower and shorter arm of the lever i is opposite the horizontal portion of the right-angled slot d, and the upper and longer arm of 65 the lever extends into the path of the pin b, carried by the arm E.

The spring of the alarm mechanism of the 70 clock is wound in the usual way by a key, or it may be wound by means of the arm E. The binding-posts F G are connected with a battery, j, and bell k, as indicated diagrammatically in connection with Fig. 1, and when the alarm is released by the clock in the usual way, and the arbor C revolves, the pin b is carried round 75 against the longer arm of the lever i and turns the lever on its pivot, releasing the contact-lever e from the horizontal part of the slot d, allowing it to drop down in the vertical part of the slot and make a contact with the wire 80 g, as shown in dotted lines in Fig. 3. The circuit being thus completed, the bell k will continue to ring so long as the lever e rests upon the wire g.

The alarm may at any time be stopped by 85 turning the lever i back into its original position and replacing the lever e in the horizontal part of the slot d.

The alarm of an ordinary alarm-clock is limited as to time by the length of the spring, 90 and it is frequently of such short duration as to be ineffectual. By the application of my improvement the alarm may be prolonged indefinitely and cannot be stopped without personal attention.

Having thus described my invention, what I claim as new, and desire to secure by Letters Patent, is—

1. The combination, with the alarm mechanism of an alarm-clock, of the arbor-extension D, the arm E and pin b, lever i, extending into the path of the pin b, the contact-lever

e, arranged to be released by the lever *i*, the contact-wire *g*, and the electrical connections, substantially as herein shown and described.

2. The combination, with the alarm-clock 5 A, provided with the arbor-extension D, the arm E, and pin *b*, of the base B, provided with the right-angled notch *d*, the wire *g*, stretched across the base, the contact-lever *e*, placed above the wire *g*, the lever *i*, pivoted to the

base B, extending into the path of the pin *b* to and adapted to engage the contact-lever *e*, and the electrical connections, substantially as herein described.

FRANK GLASGOW.
